Primary Examiner — Catherine Tuttle(74) *Attorney, Agent, or Firm* — Hunton & Williams LLP**CLAIM**

(57) We claim the ornamental design for a dispensing container, as shown and described.

DESCRIPTION

FIG. 1 is a right side view of the dispensing container.

FIG. 2 is a front view thereof; and,

FIG. 3 is a perspective view thereof.

The broken lines in the drawings are included for the purpose of illustrating the portions of the dispensing container form no part of the claimed design.
